A. D. FERGUSON

BLANK HEATING FURNACE

Filed April 5, 1922

Fig. 2.

Fig. 3.

Inventor:
Alexander D. Ferguson.

Attach. Office.

Attorney.

UNITED STATES PATENT OFFICE.

ALEXANDER D. FERGUSON, OF CHICAGO, ILLINOIS, ASSIGNOR TO SULLIVAN MACHINERY COMPANY, A CORPORATION OF MASSACHUSETTS.

BLANK-HEATING FURNACE.

Application filed April 5, 1922. Serial No. 549,928.

To all whom it may concern:

Be it known that I, ALEXANDER D. FERGUSON, a citizen of the United States, residing at Chicago, in the county of Cook and State 5 of Illinois, have invented certain new and useful Improvements in Blank-Heating Furnaces, of which the following is a full, clear, and exact specification.

My invention relates to blank heating 10 furnaces, and more particularly to blank heating furnaces for heating the blanks from which the cutter bits are made, for use in mining machines of the cutter bit type, or for heating bits requiring resharpening, or 15 for reheating bits prior to tempering.

An object of my invention is to provide an improved blank heating furnace. Another object of my invention is to provide an improved blank heating furnace which 20 will provide a constant supply of heated blanks and in which a series of blanks may be gradually brought up to the required temperature for working or tempering. A further object of my invention is to provide an 25 improved blank heating furnace provided with heating means of the hydrocarbon burner type. Other objects and advantages of my invention will hereinafter more fully appear.

In the accompanying drawings I have shown for purposes of illustration one form 30 which my invention may assume in practice.

In these drawings,—

Fig. 1 is a view partially in side elevation and partially broken away of the illustrative 35 embodiment of my invention.

Fig. 2 is a plan view of the illustrative embodiment shown in Fig. 1.

Fig. 3 is a vertical transverse section on 40 the line 3—3 of Fig. 1.

In the embodiment of my invention which I have shown and shall now describe for purposes of illustration, a heating furnace generally designated 1 together with blank 45 conveying means generally designated 2 are supported upon suitable legs 3 and 4, the furnace proper comprising a combustion chamber 5 which is herein made up of parallel lateral sides or rows of fire brick 7 between which there is arranged a fire clay or fire brick bottom 8 which slopes upward from the burner end of the furnace, as indicated in Fig. 1, while the top of the furnace is nearly closed by a row of fire brick 9 supported upon one of the sides of fire brick 55 7 and projecting nearly across the top of the combustion chamber 5 to form a long narrow vent or flue 6. The entire combustion chamber is supported in a channel-like metal frame 10 which is supported by the 60 legs 3 and 4. A burner which may be of any suitable type is shown at 11, this burner being disposed at the deeper end of the combustion chamber and projecting its flame longitudinally thereof. The fire bricks are 65 held against displacement by strap-like members 12 extending over their tops. Carried by suitable brackets or hangers 13 and 14, of which the latter is formed on the frame, at the end of the combustion chamber 70 remote from the burner is a pulley or belt wheel 15 and the frame member on which the member 14 is formed extends throughout the entire forward side of the machine and is provided at its opposite end 75 with a member 14' carrying a journal 16 in which a shaft 17 is rotatably supported. A second hanger similar to the hanger 13 may be employed, if desired, to support the shaft 17 but is not shown. Secured to the shaft 80 17 is a second belt wheel or pulley 18 to which on the opposite side of the journal 16 a gear 19 is secured. The gear 19 is driven by a pinion 20 and this pinion is driven by a 85 ratchet wheel 21 secured thereto and rotated by a pawl carrying arm 23 oscillatable about the axis of the pinion 20 and gear 21. The arm 23 carries a pawl 24 which engages with serrations 25 in the periphery of the ratchet wheel 21. Any suitable supporting 90 means may be employed for the wheel 21, the pinion 20, and the arm 23, these being shown herein as supported upon a depending bracket 26 secured to the members 14 and rigidly supporting a shaft 27 upon which the 95 gear and pinion are rotatable and the arm 23 oscillatable. For the purpose of oscillating the arm, a link 28 is connected with an adjustable block 29 adjustably movable in a slot 30 in a gear 31 which is journaled in a suitable hanger 32 on the frame and driven by a gear 33 on a power shaft 34 which is driven by a pulley 35 at the back of the machine. An endless sheet metal belt 36 passes around the peripheries of the wheels 15 and 18 and passes over the top of the front row or wall of fire brick 7 and the strap 12 which holds them in position.

- As the pulley 35 is rotated, the belt 38 is caused to travel with its top strand moving from right to left and a series of bits are laid thereon at the right hand end thereof and then move along, as indicated at 40 in Fig. 2, with their ends 41 projecting into the slot 6 formed between the top of the fire brick 7 and the adjacent side of the fire brick 9.
5. In a blank heating furnace, a combustion chamber comprising parallel side walls, an inclined bottom, and a top supported upon one of said side walls and terminating short of the other, and means including a conveyor running along the other of said side walls for supporting a series of bits over the vent formed between said last mentioned side wall and said top. 70
10. As a result of this construction, it will be noted that the metal conveyor belt is protected from direct contact with the flame from the burner while the bits are subjected, as to their points, which is the only portion 75 requiring heating, to the full heat of the blast and as the maximum heat is generated near the left hand end of the combustion chamber, the bits are progressively subjected to more and more intense heat. Owing to the shape of the combustion chamber, a great amount of heat is transmitted to the bits by radiation as well as being imparted thereto by the combustion products and, by reason of the disposition of the bits 80 in the only path of escape of the combustion products from the combustion chamber, the heat is most efficiently used.
15. In a blank heating furnace, a combustion chamber having an inclined bottom and a longitudinally arranged vent at the top thereof, and a belt conveyor moving outside the path of combustion products through said vent for supporting a series of blanks 85 projecting into said vent.
20. In a blank heating furnace, a combustion chamber having a longitudinally directed burner, and means including a conveyor arranged wholly outside said chamber for 85 conducting a series of blanks along said chamber to discharge adjacent the hottest point therein.
25. In a blank heating furnace, a combustion chamber having a longitudinally directed burner, and means including a conveyor running along the top of said combustion chamber for conducting a series of blanks 90 along said chamber to discharge adjacent the hottest point therein. 95
30. While I have in this application specifically described one form which my invention may assume in practice, it will be understood that this form of the same is shown for purposes of illustration and that the invention may be modified and embodied in various other forms without departing from 100 its spirit or the scope of the appended claims.
35. What I claim as new and desire to secure by Letters Patent is:
1. In a blank heating furnace, a substantially horizontal combustion chamber having an inclined bottom and a longitudinally directed burner, and means including a conveyor for conducting a series of blanks along 105 said combustion chamber.
  2. In a blank heating furnace, a combustion chamber having an inclined bottom, a substantially horizontal top, and a relatively narrow longitudinally extending flue or vent at the top thereof, and means including a conveyor for conducting a series of blanks along 110 said vent.
  3. In a blank heating furnace, a combustion chamber having a longitudinally disposed vent at the top thereof, and means including a conveyor to one side of said vent for conducting a series of blanks along 115 said vent to discharge adjacent the hottest point therein.
  4. In a blank heating furnace, a combustion chamber having an inclined bottom and a relatively narrow longitudinal slot at the top thereof, a burner discharging longitudinally of said combustion chamber from the deeper end thereof, and means for conveying a series of blanks with portions thereof 120 projecting across said vent.
  5. In a blank heating furnace, a combustion chamber having an inclined bottom and a burner located at the deepest point therein and discharging towards the shallowest point therein, and a conveyor adapted 125 to convey a series of blanks in the path of the combustion products to discharge the blanks of highest temperature at the shallow point in said chamber.
  6. In a blank heating furnace, a combustion chamber having an inclined bottom and a burner located at the deepest point therein and discharging towards the shallowest point therein, and a conveyor adapted 130 to convey a series of blanks in the path of the combustion products to discharge the blanks of highest temperature at the shallow point in said chamber.
  7. In a blank heating furnace, a combustion chamber having a longitudinally directed burner, and means including a conveyor arranged wholly outside said chamber for 135 conducting a series of blanks along said chamber to discharge adjacent the hottest point therein.
  8. In a blank heating furnace, a combustion chamber having a longitudinally directed burner, and means including a conveyor running along the top of said combustion chamber for conducting a series of blanks along said chamber to discharge adjacent the hottest point therein.
  9. In a blank heating furnace, a combustion chamber having an inclined bottom and a top arranged so that the top and bottom approach towards the upper end of the latter, a burner discharging longitudinally thereof, and means including a conveyor for 140 conducting a series of blanks along the top of the combustion chamber to discharge adjacent the hottest point therein.
  10. In a blank heating furnace, an elongated combustion chamber having a bottom so formed as to produce a point of maximum heat at one end thereof, and means including a conveyor for conducting a series of blanks longitudinally of said chamber to 145 discharge adjacent the hottest point therein.
  11. In a blank heating furnace, a combustion chamber having a narrow longitudinally extending flue and a burner discharging a gaseous mixture longitudinally thereof, and a conveyor adapted to convey a series of blanks along the top of said flue to discharge adjacent the point of highest temperature.
  12. In a blank heating furnace, a combustion chamber having an inclined bottom and a burner located at the deepest point therein and discharging towards the shallowest point therein, and a conveyor adapted 150 to convey a series of blanks in the path of the combustion products to discharge the blanks of highest temperature at the shallow point in said chamber.
  13. In a blank heating furnace, a horizontal combustion chamber having an in-

clined bottom and a graduation of heat therein along its length, and a conveyor adapted to convey a series of blanks along said chamber to discharge adjacent the hot 5 test point therein.

14. In a blank heating furnace, a combustion chamber horizontally disposed and having its bottom inclined longitudinally, a burner discharging longitudinally thereof, and a conveyor adapted to convey a series of blanks along said chamber and discharge at the top of said inclined bottom. 10

15. In a blank heating furnace, a tapered combustion chamber having an inclined bottom and a longitudinally directed burner, and means including a conveyor for conducting a series of blanks along said combustion chamber towards the smaller end thereof. 15

16. In a blank heating furnace, an elongated combustion chamber, and means including a conveyor for conducting a series of blanks longitudinally of and over said chamber to discharge adjacent the hottest point therein. 20

25. 17. In a blank heating furnace, an elongated substantially horizontal combustion chamber having an inclined bottom and a burner discharging therein, and means for conducting a series of blanks longitudinally along said chamber. 30

35. 18. In a blank heating furnace, an elongated combustion chamber provided with an inclined bottom and a substantially horizontal top, and means for conducting a series of blanks longitudinally thereof having portions projecting over said chamber along said top. 40

40. 19. In a blank heating furnace, an elongated combustion chamber provided with an inclined bottom and a substantially horizontal top, and means for conducting a series of blanks longitudinally thereof projecting over said chamber along said top to discharge adjacent the hottest point in said chamber. 45

45. 20. In a blank heating furnace, an elongated combustion chamber having an inclined bottom, means including a conveyor for conducting a series of blanks longitudi-

nally along said chamber, and means for 50 driving said conveyor at variable speeds.

21. In a blank heating furnace, an elongated combustion chamber provided with an inclined plane bottom and a burner discharging therein, and means to guide a series 55 of blanks through said chamber to discharge adjacent a point oppositely disposed from said burner discharge.

22. In a blank heating furnace, a combustion chamber provided with an inclined bottom and a burner discharging therein, and means to guide a series of blanks through 60 said chamber to discharge the blanks of highest temperature adjacent a point oppositely disposed from said burner discharge. 65

23. In a blank heating furnace, an elongated tapered combustion chamber having an inclined bottom, and means including an endless belt conveyor for conducting a series 70 of blanks longitudinally along said chamber.

24. In a blank heating furnace, an elongated tapered combustion chamber having an inclined bottom and a horizontally disposed flue, and means for conducting a series 75 of blanks longitudinally along said flue.

25. In a blank heating furnace, an elongated tapered combustion chamber having an inclined bottom and a flue, and means for conducting a series of blanks longitudinally 80 along said flue to discharge the blanks adjacent the hottest point in said chamber.

26. In a blank heating furnace, an elongated tapered combustion chamber having an inclined bottom and a longitudinally disposed vent at the top thereof and means including a conveyor arranged at one side of 85 said vent for conducting a series of blanks longitudinally along said vent to discharge adjacent the hottest point in said chamber. 90

27. In a blank heating furnace, an elongated tapered combustion chamber having an inclined bottom and a burner discharging upwardly along said bottom, and means for conducting a series of blanks longitudinally along said chamber. 95

In testimony whereof I affix my signature.

ALEXANDER D. FERGUSON.
